John Wiedersheim, ATTORNEY.

UNITED STATES PATENT OFFICE.

FRANK MANNING, OF ARDMORE, PENNSYLVANIA.

ROCK-DRILL.

SPECIFICATION forming part of Letters Patent No. 337,968, dated March 16, 1886.

Application filed September 3, 1885. Serial No. 176,051. (No model.)

To all whom it may concern:

Be it known that I, FRANK MANNING, a citizen of the United States, residing in Ardmore, county of Montgomery, State of Pennsylvania, have invented a new and useful Improvement in Rock-Drills, which improvement is fully set forth in the following specification and accompanying drawings, in which—

10 Figures 1 and 2 represent side elevations of a rock-drill embodying my invention. Fig. 3 represents a horizontal section thereof in line *x x*, Fig. 1.

Similar letters of reference indicate corresponding parts in the several figures.

15 My invention consists of a rock-drill or quarrying-machine provided with means whereby the bits are powerfully struck and reliably rotated and possessing other advantages, as will be hereinafter fully set forth.

20 Referring to the drawings, A represents the frame of the rock-drill, and B represents a power or driving wheel mounted on the upper portion thereof.

25 C represents a rotary-shaft, which extends vertically, and is mounted in cross-heads D D' D'' of the drill or machine. Projecting from said shaft C are arms or pins E, which are adapted to be engaged by lateral projections *a* on the side of a cam, F, the latter being secured to or formed with the driving-wheel B, whereby the rotation of said cam with the wheel imparts rotary motion to the shaft C.

30 G represents a ram or hammer, which is guided in uprights of the frame A, and connected at top with an upright stem, H, to which is secured an arm, J, so disposed that it may be engaged by the cam F on the wheel B.

35 K represents bits or cutters, which are fitted at their upper ends into heads L, said bits and heads being properly guided in the lower part of the frame A, the heads being beneath the ram G, so as to be struck by the same. The heads have connected with them pinions or gear-wheels M, which mesh with each other, one of the pinions meshing with a pinion, N, on the lower end of the shaft C, it now being evident that the rotation of the shaft C causes 40 rotation of the heads L and consequently of the bits K. The connection of the wheels M and heads L is by means of feathers, whereby

said heads may move vertically in said wheels or rise and fall therein.

It will be seen that when power is applied 55 to the wheel B the cam F engages with the arm J, thus raising the ram G, and also with the arms E, thus rotating the shaft C, and owing to the gearing N rotating the bits. When the cam F clears the arm J, the stem H 60 is no longer controlled by the cam, and the ram drops, its forcible descent being assisted by a spring, H', which bears downwardly against the arm J, or may bear against any suitable part of the stem or ram, and a powerful blow is imparted to the heads L and consequently to the bits K. The ram is then 65 raised and the bits are elevated by springs K' and rotated, after which the ram again drops, causing the bits to cut to a greater depth, and the operations are repeated and continued as desired, the blows of the ram increasing in power as the depth of the holes increases.

70 The base portion of the carriage is mounted on rollers P, whose bearing-stems Q are passed through said base and pierced to receive pins S, whereby the frame may be raised and lowered in order to adjust the depth of penetration of the bits.

75 In order to guide the machine true during 80 the drilling operation, there is attached to the base portion of the frame an arm or bar, T, in which are fitted pins U, which, after the first set of holes are drilled, are dropped thereinto, and the next set of holes are drilled, said pins 85 are raised, the drill or machine is moved, and the pins are dropped into the last-named holes, and thus the guiding of the machine is continued, as desired.

Having thus described my invention, what 90 I claim as new, and desire to secure by Letters Patent, is—

1. The driving-wheel B, having cam F, with projection *a* on the side of the said cam, in combination with the vertical rotary shaft C, 95 provided with suitable bearings and having horizontal arms E, and gears for rotating a series of drills, substantially as and for the purpose set forth.

2. The wheel B, with cam F, having lateral 100 projections *a*, and rotary shaft C, having horizontal projections E, adapted to engage the said projections *a*, and thereby operate a series of drill-rotating gears, in combination with

hammer G, having vertical stem H, provided with arm J, and spring H', substantially as and for the purpose set forth.

3. A rotary wheel having a cam, in combination with a vertical rotary shaft having pins thereon adapted to be brought in contact with lateral projections on said cam, and a hammer having a handle with projecting arm, the latter by its contact with the cam of the wheel imparting a rising and falling motion to the said hammer, substantially as described.

4. The bit K, in combination with the frame A, head L, with feather, wheel M, mounted on the head A, pinion N, mounted 15 on the shaft C, the shaft C, having horizontal

projections E, and wheel B, having cam with lateral projections a, substantially as and for the purpose set forth.

5. In a rock-drill or quarrying-machine, the frame A, in combination with the horizontal perforated bar T, attached to said frame and having adjustable pins U, adapted to be inserted in the perforations of said bar and in the drill-holes in the rock, whereby the carriage is anchored, substantially as and for 25 the purpose set forth.

FRANK MANNING.
